ATTORNEY

UNITED STATES PATENT OFFICE.

JOHN F. DANIKEN, OF ADONIS, MISSOURI.

VALVE-SPRING TOOL.

Application filed January 16, 1922. Serial No. 529,598.

To all whom it may concern:

Be it known that I, JOHN F. DANIKEN, a citizen of the United States, residing at Adonis, in the county of Polk and State of Missouri, have invented new and useful Improvements in Valve-Spring Tools, of which the following is a specification.

This invention relates to tools especially designed for use in removing valves from internal combustion engines and has for an object the provision of a tool by means of which the valve spring may be compressed to facilitate the removal of the valve.

Another object of the invention is the provision of a tool as above set forth, which is adjustable to permit of its use with valves of different lengths and upon engines where the valves are differently positioned, the invention thus providing a tool whose use as a valve spring tool is universal.

With the above and other objects in view, the invention further includes the following novel features and details of construction, to be hereinafter more fully described, illustrated in the accompanying drawings and pointed out in the appended claims.

In the drawings:

Figure 1 is a side elevation of a tool constructed in accordance with the invention and illustrating its application when in use.

Figure 2 is a top plan view of the same.

Figure 3 is an edge view.

Figure 4 is a section on the line 4—4 of Figure 1.

Figure 5 is a view similar to Figure 1 but showing the position of the parts when the valve spring is compressed.

Referring to the drawings in detail, wherein like characters of reference denote corresponding parts, the tool which comprises the subject matter of the present application includes a frame having right angularly disposed members 10 and 11, the said frame further including an angle piece 12 to which is secured upon opposite sides, plates 13, the latter forming the member 10. The member 12 is of sectional formation one of the said sections being formed by the angle piece 12 and the other section being formed by spaced plates 14 which are adjustably secured to the member 12 through the medium of bolts 15 and thumb nuts 16. One of these bolts is carried by each section of the member 12 and each of the said bolts passes through a slot in the said sections. For example, the bolt 15 passes through a

slot 17 provided in the section which is formed by the angle piece 12, the said bolt connecting the spaced plates 14. The other bolt 15 is carried by the member 12 and extends through a slot 18 provided in each of the plates 14, the thumb nut 16 serving to hold the sections in adjusted position.

Pivotedly mounted upon a bolt 19 between the plates 14 is an arm 20, the said arm being provided with spaced openings 21 whereby its pivotal point may be adjusted. One end of this arm is bifurcated as shown at 22 for the reception of the stem 23 of a valve 24. The usual spring 25 surrounds the stem 23.

The opposite end of the arm 20 is connected by means of a link 26 with an operating lever 27, a pivot pin 28 serving for this purpose. The inner end of the operating lever 27 is pivotally secured to the frame upon one of the bolts 15 as shown.

In addition there is provided a supplemental lever 29, which is pivotally mounted as at 30 upon one member of the frame. One end of this lever engages the arm 20 near the valve engaging end of this arm, while the opposite end of the lever 29 is connected by a link 31 to the operating lever 27, the pivot 28 which connects the link 26 with this lever serving for this purpose.

Carried by the member 10 of the frame and positioned between the plates 13 of this member is a valve engaging element 32. This element is adapted for engagement with the valve 24 and is mounted between the plates 13 upon a bolt 33, which bolt is removably received within openings 34 so as to adjustably position the element 32.

In the use of the invention the tool is positioned as illustrated in Figure 1. A downward movement of the outer end of the operating lever 27 will move the inner end of the arm 20 upward so as to compress the same as illustrated in Figure 5 of the drawings, whereupon the valve may be readily removed.

By adjusting the sections of the member 11 of the frame, the tool may be adjusted to valves of different lengths, while it may be also adapted for use with different types of engines where the position of the valves within the cylinder block may vary. The tool is adjusted to the length of the valve through the adjustment of the member 11, while the element 32 may be moved longitudinally of the member 10 of the

frame to properly position the said element for engagement with the valve.

For the purpose of holding the valve springs in compressed position, there is mounted upon the pivot pin 28, a dog 35, which is adapted for engagement with a series of spaced notches 36 provided in the member 12. Pivottally mounted upon the operating lever 27, as shown at 37 is an arm 38 which is connected to the dog 35 by a link 39. A spring 40 connecting the arm 38 and the lever 37 serves to normally force the dog 35 into engagement with the notches in the member 12.

When the valve spring has been compressed by the use of the tool, the dog 35 will engage one of the notches 36 and hold the spring in compressed position until said dog is released by operating the pivoted arm 38.

The invention is susceptible of various changes in its form, proportions and minor details of construction and the right is herein reserved to make such changes as properly fall within the scope of the appended claims.

Having described the invention what is claimed is:

1. A valve spring tool comprising a frame including right angularly arranged members, a valve engaging element carried by one of said members, a spring engaging arm pivotally mounted upon the other member, an operating lever pivotally secured to the frame and a link connecting the arm and lever.

2. A valve spring tool comprising a frame including right angularly arranged members, a valve engaging element carried by

one of said members, a spring engaging arm pivotally mounted upon the other member, an operating lever pivotally secured to the frame, a link connecting the arm and lever, a supplemental lever pivotally secured to the frame and engageable with said arm and a link connecting the supplemental lever with the operating lever. 40 45

3. A valve spring tool comprising a frame including right angularly arranged members, one of said members being of sectional formation and including a pair of spaced plates, means for adjustably connecting the spaced plates to the other section of said member, an arm pivotally and adjustably mounted between the spaced plates, means located at one end of said arm for receiving the valve stem, whereby the arm may engage the valve spring, an operating lever pivotally secured to the sectional member of the frame, a link connecting the arm and operating lever and means adjustably secured to the other member of the frame for engagement with the valve.

4. A valve spring tool comprising a frame including right angularly arranged members, a valve engaging element carried by one of said members, a spring engaging arm pivotally mounted upon the other member, an operating lever pivotally secured to the frame, a link connecting the arm and lever and a latch carried by the operating arm and engageable with the frame for holding the tool in adjusted position. 65 70

In testimony whereof I affix my signature.

JOHN F. DANIKEN.
